US00D934277S

(12) **United States Design Patent** (10) **Patent No.:** **US D934,277 S**
Park (45) **Date of Patent:** **** Oct. 26, 2021**

(54) **DISPLAY PANEL OF PROGRAMMED COMPUTER SYSTEM WITH GRAPHICAL USER INTERFACE**

(71) Applicant: **CLO Virtual Fashion Inc.**, Seoul (KR)

(72) Inventor: **Miseon Park**, Seoul (KR)

(73) Assignee: **CLO VIRTUAL FASHION INC.**, Seoul (KR)

(**) Term: **15 Years**

(21) Appl. No.: **29/751,205**

(22) Filed: **Sep. 18, 2020**

(30) **Foreign Application Priority Data**

Apr. 27, 2020 (KR) 30-2020-0018721

(57) **CLAIM**

The ornamental design for a display panel of a programmed computer system with a graphical user interface, as shown and described.

DESCRIPTION

The FIGURE is a front view of a display panel of a programmed computer system with a graphical user interface, showing my new design.

The outermost broken-line rectangle illustrates the display panel and forms no part of the claimed design. The remaining broken lines illustrate portions of a graphical user interface and form no part of the claimed design.

1 Claim, 1 Drawing Sheet
